UNITED STATES PATENT OFFICE

2,635,241

BRASSIÈRE

Fred V. Graf, Los Angeles, Calif.

Application June 14, 1948, Serial No. 32,822

1 Claim. (Cl. 2—42)

1

This invention relates to an improvement in brassières and is particularly directed to the open top breast cups, designed of a plurality of circular ring sectors with arcuate side edges sewed to each other, except the two outer sectors which have straight edges and when the bases of said sectors are secured to a pair of apertures of the body portion of the brassière which are positioned at the breast of the wearer, said breast cups have a larger cubic inch displacement than the conventional breast cups, due to the hollow semi-spherical design, but will give the breast a smaller appearance. Said breast cups cover the major lower part of approximately four-fifths of the wearer's breast, leaving approximately one-fifth of open space at the upper portion of the breast cups and thus exposing the breast. Breast cups formed in this manner are revolutionary and new in the art.

Another most important feature of the invention is that the open cups mold and comfortably support the breasts of any size or type and imparts to them the desired uplift and separation, in addition they strengthen the muscles of a youthful breast at the time of development, as it is held up in a natural position and fully supported by these dome shaped breast cups, which might be likened to an "Eskimo igloo," and not flattened against the body like in some of the conventional brassières.

Another object of this invention is a brassière comprising a body embracing portion having a pair of apertures positioned at the breast of the wearer, and an open top breast cup secured to said body portion and covering the major part of each aperture respectively.

Another very important feature of this invention is that these hollow semi-spherical shaped breast cups comfortably and snugly house the breast of a large, sagging nature and prevents the breasts from moving or slipping out from under or along the sides as in most of the brassières, but allows the breasts to come out thru the open top, which gives an extra uplift and comfort to the wearer. The opening at the top of the breast cups also acts as a ventilator. Any part of the brassière can be made from any suitable material including rubber.

This invention possesses many other advantages which may be more clearly apparent from the following detailed specification shown in the accompanying drawings.

Referring to the drawings, which illustrate the invention, which has been reduced to practice,

Fig. 1 is a front elevation of the brassière

2

showing the open top breast cup, as it appears when in an extended condition.

Fig. 2 is a fragmentary front elevation of the lower, central portion of the brassière showing the same opened.

Fig. 3 is a plan view illustrating the segments of the brassière of Fig. 1 slightly separated from each other, but approximately in their assembled relation.

10 Fig. 4 is a perspective view illustrating the brassière with the opening with its segments constructed as shown in Fig. 3, in place upon the body of the wearer.

Fig. 5 is an enlarged fragmentary, front view 15 of the eyelet band and strap portion of the brassière.

Fig. 5a is a view looking at the left side of Fig. 5.

20 Fig. 6 is a top side view of a sponge rubber member which is slidable on the shoulder strap.

Fig. 6a is a side elevation of the member shown in Fig. 6.

Fig. 7 is a front elevation showing the brassière with openings at the apex, in an extended 25 condition.

Fig. 8 is a perspective view showing the brassière of Fig. 7 in place upon the body of the wearer.

Fig. 9 is a plan view illustrating the segments 30 of the brassière of Figs. 7 and 8, slightly separated from each other, but in approximately their assembled relation.

Fig. 10 is a plan view showing the open top 35 breast cups surrounded by the body portion, in an extended condition, lacing being shown instead of a zipper.

Fig. 11 is a front perspective view of the brassière of Fig. 10 with open top breast cups, in place upon the body of the wearer.

40 Fig. 12 is a view similar to Fig. 3 except that there are no eyelets in the upper two segments shown. This form of breast cup belongs to Figs. 10 and 11.

Referring to Figs. 1 and 10, the garments include a reenforced lower body structure 1, two open top breast receiving pockets 12 and 13, the complete breast cups 12 and 13 with center openings 32 as shown in Fig. 7. On all the illustrated brassières the lower reenforced arched body portion 1 clings to the body and holds firmly by fastening means 10 and 11. Figs. 3 and 12 are breast cup segments resembling circular ring sectors 14 with arcuate side edges 15, two top segments 18 and 19 with the straight inner edge 55 15a, the side edges 15 are sewed to each other to

form a partially open breast cup and when the base portion 14^a is sewed into the aperture 2 of body portion 1, the straight edges 15^a of segments 18 and 19 surround the open spaces 16 and 17 on the upper portion of the breast cups. This design forms hollow semi-spherical breast cups which have a larger cubic inch displacement.

Various changes may be made in details of the construction without departing from the invention.

In the applicant's finished breast cup about three hundred and twenty degrees of unbroken material contacts the surface of the wearer's breast, leaving a permanently open space of approximately forty degrees at the top of the breast cup, thus forming a hollow approximately semi-sphere, and relieving the upper part of the breast from pressure, and insuring comfort to the wearer, see Fig. 11.

It is difficult to sew smoothly into place, within a circular opening, the basal part of a hollow, semi-spherical breast cup; because it is difficult for a seamstress to avoid pulling unequally on the cup and the surrounding fabric, causing an unsightly appearance, and detracting from the wearing comfort of the brassière. But when a part of the breast cup is cut away before said cup is sewed in, this difficulty disappears, because there is no objection to a slight variation in the width of the upper part of the opening in the

breast cup. This enables the seamstress easily and smoothly to sew the cup into place, as shown in Figs. 10 and 11.

I claim:

- 5 In a brassière, a body encircling band having breast receiving apertures therein, a partially open cup, partially closing each of said apertures and stitched to said body encircling band, each of said cups comprising a plurality of circular ring sectors, each sector having arcuate side edges, said side edges of adjacent sectors being secured to each other to form a curved lower edge of approximately 300 degrees and being adapted to form a hollow approximately semi-spherical open top brassière cup.

FRED V. GRAF.
